DISPENSING CONTAINER

Morton McI. Dukehart, Jr., New Rochelle, N. Y.,
assignor to Continental Can Co., Inc., New
York, N. Y., a corporation of New York

Application September 17, 1941, Serial No. 411,211

3 Claims. (Cl. 221—62)

The present invention relates to new and useful improvements in containers, and more particularly to improvements in a dispensing container having a closure which may be selectively tilted to various positions for controlling the dispensing openings.

According to the present invention, the container includes a body portion which is preferably rectangular and which includes side and end walls. Both ends of the body portion are closed but opposed side or end walls at one end thereof are provided with pouring and sifting openings. Thus, the contents of the container may be poured or sifted through the corresponding dispensing openings by tilting the container. However, the dispensing openings are normally covered by the closure which is tiltably connected to the adjacent end of the container. This closure is adapted to selectively control the dispensing openings and may be tilted from a horizontal position covering and closing the dispensing openings to alternate tilted positions either uncovering the pouring opening or uncovering the sifting openings.

An object of the present invention is to provide a dispensing container of the above type wherein the ends of the container are horizontally closed but opposed side walls of the container are formed with pouring and dispensing openings which are adapted to be controlled by a tiltable closure.

Another object of the present invention is to provide a dispensing container of the above type wherein the closure may be selectively tilted from a neutral position covering the dispensing openings to one position exposing the pouring opening or to another position exposing the sifting openings.

A further object of the invention is to provide a dispensing container of the above type wherein the closure may be tilted about either one of a pair of hinge axes each of which consists of a snap connection between the closure and the container.

A still further object of the invention is to provide a dispensing container of the above type wherein both hinge connections between the closure and the container are in engagement when the closure is in a neutral position covering all the dispensing openings.

The above and other objects of the invention will in part be obvious and will be hereinafter more fully pointed out.

In the accompanying drawing:

Figure 1 is a side elevation of the container with the broken lines indicating the closure in one of its selected open positions.

Figure 2 is a side elevation of Figure 1 showing the dispensing openings.

Figure 3 is an enlarged fragmentary sectional view taken along the line 3—3 of Figure 2.

Figure 4 is an enlarged fragmentary sectional view taken along the line 4—4 of Figure 1.

Figure 5 is a top plan view of the container.

Referring more in detail to the accompanying drawing, the container includes a body wall 10 which is preferably rectangular in shape and which includes side and end walls. The bottom of the body wall is closed by an end 11 which may be secured thereto by a conventional double seam or the like. The opposite or top end of the body wall is provided with a reduced rectangular neck portion 12 below which there is provided an outward peripheral strengthening bead 13.

The top end of the body portion is closed by a friction cover 14 having opposed end walls 15, 15a and opposed side walls 16, 16a. These side and end walls depend from an imperforate horizontal top closing wall 17 and are adapted to fit over and frictionally engage the neck portion 12 on the container. As illustrated in the accompanying drawing, the end wall 15 is provided with a pouring opening 18 and the end wall 15a is provided with sifting openings 19, these openings being disposed near the top closing wall 17. The side walls 16, 16a are provided with outwardly extending ribs 23, 26a, respectively, which may serve as finger grips for facilitating removal of the cover 14 from the container in order to permit the contents of the container to be withdrawn by insertion of a spoon or the like.

A control member 21 in the form of a closure is connected to the container for selective tilting movements in order to selectively control the pouring opening 18 and the sifting openings 19. The closure member 21 is provided with a horizontal top closing wall 22 and with depending side walls 23, 23a and also with depending end walls 24, 24a. The side and end walls fit over the corresponding side and end walls of the cover 14 and the end walls 24, 24a are adapted to control the pouring opening 18 and the sifting openings 19, respectively.

The side wall 16 of the cover 14 is provided with longitudinally spaced inwardly extending dimples 25, 25a which are disposed slightly above the rib 26. Similarly, the side wall 16a is provided with similarly spaced inwardly extending dimples or recesses 26, 26a which are disposed above the rib 23a. The side wall 23 of the closure member 21 is provided with inwardly extending projections 27, 27a which are spaced symmetrical- 50 ly with respect to the dimples 25, 25a and which are adapted to cooperate therewith for effecting the desired tilting of the closure. The side wall 23a of the closure member 21 is also provided with similarly spaced inward projections 28, 28a which are adapted to cooperate with the recesses 26, 26a in the side wall 16a.

The horizontal portion 22 of the closure 21 is 55 provided with spaced depressed portions 29, 30

on each side thereof which are adapted to engage the top 17 of the cover 14 when the closure 21 is in a neutral position covering dispensing openings at each end thereof. Thus, the depressed portions on the closure serve to space the top wall 22 thereof slightly above the top wall 17 of the cover 14. The end walls 24, 24a are shorter than the side walls 23, 23a which are cut away along inclined lines 31, 31a from the end walls to a point substantially in line with the adjacent inward projections.

When the closure member 21 is in the position shown in Figure 3, the inward projections 27, 27a fit within the recesses 25, 25a and similarly, the inward projections 28, 28a fit within the recesses 26, 26a and the closure member is thus maintained in a substantially horizontal position with the depressed portions on the top wall 22 thereof bearing against the top wall 17 of the cover 14. In this position of the closure member, the end wall 24 covers and closes the pouring opening 18 and the end wall 24a covers and closes the dispensing openings 19. When it is desired to uncover the sifting openings 19, the closure member 21 is tilted to the position shown by the broken lines of Figure 1. In this position of the closure member, the inward projections 27a, 28a are shifted out of their corresponding recesses 25a, 26a and the cover is adapted to hinge along the axes of the inward projections 27, 28 which remain in engagement with their corresponding recesses 25, 26. In this position of the closure member it will be seen that the bottom edge of the end wall 24a has been elevated so as to uncover the dispensing openings 19. The closure member is limited in its tilting movement by binding engagement between the edges of the end walls and the end walls of the cover 14 and the inclined or cut away portions 31, 31a of the side walls of the cover serve to permit, together with the slight flexibility of the material, this tilting movement of the closure member. When it is desired to uncover the pouring opening 18, the closure member 21 may be tilted in the opposite direction with the axes of the projections 27a, 28a serving as the hinge axis. In order to prevent the fingers or thumb from slipping off the closure 21 when shifting the same to one of its selected tilted positions, roughened or ribbed surfaces 32 are provided at each end thereof for engagement with the fingers or thumb.

From the foregoing description, it will be seen that the present invention provides a highly efficient dispensing container having a pouring opening and sifting openings formed in opposite end walls of the body wall of the container or, as in the illustrated embodiment of the invention, these dispensing openings are formed in the end walls of a closure for one end of the container. The closure for controlling the dispensing openings is shiftable from an intermediate neutral position covering the pouring opening and the sifting openings to selected tilted positions uncovering either the pouring opening or the sifting openings. The side and end walls of the closure member are shaped so as to facilitate tilting movement thereof and to also limit this tilting movement. The side walls are formed to cooperate with the side walls of the cover for the container so as to provide at least one hinge point for the closure member. As illustrated, however, the

closure member has two hinge connections adjacent each end of the container cover and these hinge connections become selectively operable depending upon the manner in which the closure member is tilted, although a single central hinge connection may be employed if so desired. In the neutral position of the closure member, the pouring opening and the sifting openings are covered by the end walls of the closure member and the depending projections on the closure member serve to properly locate the same with respect to the dispensing openings.

While one form of the invention has been shown for purposes of illustration, it is to be clearly understood that minor changes in the details of construction and arrangement of parts may be made without departing from the scope of the invention as set forth in the appended claims.

I claim:

1. A dispensing container comprising a substantially rectangular body portion with opposed peripheral end walls provided with dispensing openings therethrough, and a substantially rectangular closure member fitting over one end of the body portion and having the peripheral end walls thereof adapted to control the dispensing openings, and the peripheral side walls of said body portion and said closure member having cooperating pairs of projections and recesses selectively providing a pivotal connection for the closure member permitting limited tilting thereof from a neutral position covering the dispensing openings to selected tilted positions uncovering one or another of the dispensing openings.
2. A dispensing container comprising a substantially rectangular body portion with opposed peripheral end walls provided with dispensing openings therethrough, and a substantially rectangular closure member fitting over one end of the body portion and having the end walls thereof adapted to control the dispensing openings, and the peripheral side walls of said body portion and of said closure member having spaced cooperating projections and recesses providing for the closure member a pair of spaced pivotal connections selectively operable to permit limited tilting of the closure member from a neutral position covering the dispensing openings to selected tilted positions uncovering one or another of the dispensing openings.
3. A dispensing container comprising a substantially rectangular body portion with opposed peripheral end walls provided with dispensing openings therethrough, and a substantially rectangular closure member provided with peripheral side and end walls fitting over the peripheral walls of said body portion with corresponding opposed peripheral end walls adapted to control the dispensing openings, the peripheral side walls of said body portion and of said closure member having cooperating projections and recesses providing a pivotal connection for the closure member permitting limited tilting thereof from a neutral position covering the dispensing openings to selected tilted positions uncovering one or another of the dispensing openings, and the top wall of said closure member having spaced downward projections abutting against the top of said body portion for properly positioning the said closure member in its neutral closing position.

MORTON McI. DUKEHART.
